GEORGE JOHN STEVENS, OF LONDON, ENGLAND, ASSIGNOR, BY MESNE ASSIGNMENTS, TO AMERICAN ATTACHMENT COMPANY, OF PORTLAND, MAINE, A CORPORATION OF MAINE.

ATTACHMENT FOR SEWING-MACHINES FOR PRODUCING FELLING, BLINDSTITCHING, &c.

No. 869,990.

Specification of Letters Patent.

Patented Nov. 5, 1907.

Application filed May 15, 1902. Serial No. 107,436.

To all whom it may concern:

Be it known that I, GEORGE JOHN STEVENS, mechanical engineer, of 25 East Lake road, Loughborough Junction, London, S. W., England, have invented a 5 certain new and useful Attachment for Sewing-Machines for Producing Felling or Blindstitching, Serging or Overcasting, Stoating or Overseaming, and Fancy and Ornamental Stitching and the Like; and I do hereby declare that the following is a full, clear, and 10 exact specification of the same.

The object of this present invention is to simplify the construction of such attachments; to reduce the expense of manufacture; to reduce the usual number of parts and to make the action of the parts more positive; 15 to secure a direct connection of the operating lever to the needle-bar, and cause the same to be operated thereby in a smooth, easy and continuous manner, and without unnecessary and harmful vibrations; to properly time the movements of the pusher and its operating 20 lever, so that while the pusher will be extended at the proper time to do its work that it will be retracted when and while the feed of the machine is feeding the work forward; to improve the construction of the pusher and its operating lever, and to improve and simplify the 25 construction and operation of the parts by which the reciprocation of the pusher is effected. I accomplish this object by certain novel features of construction and operation which are fully described in this specification and shown in the drawings, the particular features 30 of novelty constituting my invention being particularly pointed out in the claims annexed hereto.

In the drawings, which form a part of this specification and in which similar letters of reference indicate corresponding parts wherever they occur:—Figure 1, 35 is a perspective view showing my improved attachment upon a sewing machine, with work properly folded for felling in place thereupon. Figs. 2, and 3, are side elevations of the attachment. Fig. 4, is a plan view of the same. Figs. 5, 6, and 7, are plan views of the interior of the attachment, the top plate, elbow-lever, draw lever and guide having been removed. Fig. 5, 40 showing the parts in the position they are caused to assume when the pusher is extended, and Fig. 6 showing the same parts in the positions they are caused to 45 assume when the pusher is retracted, and Fig. 7 showing the parts in the position they assume when the pusher is retracted and the plunger comes forward to turn the alternator to the right hand side of the attachment. Fig. 8 is an end view of the attachment, looking 50 from the front toward the back. Fig. 9 is a plan view of the interior similar to Figs. 5, 6, and 7, showing the parts in the position they assume when the alternator has been turned toward the left hand side of the attach-

ment and the plunger has been retracted. Fig. 10 is a 55 partial detail sectional view of one end of the attachment showing the hood, draw-lever, plunger and pusher, and Fig. 11 is an enlarged detail view of the end of the draw-lever.

In this attachment, as in the attachment described in my application (Serial Number 77088) filed September 30th, 1901, I form the body in the form of a nearly closed box or case, out of three plates A, A¹, A², of thin steel, the center of the middle plate being cut away somewhat (as is clearly shown in Figs. 5 and 6) so as to receive and contain the pusher, an alternator, and the lever that operates the pusher etc. The plates A, A¹ and A², are secured together by the screws a, or in any other suitable manner. Upon the top plate A², near the front side, and to the back of the attachment I secure a standard B by means of the two screws b, b, which pass through 70 slots b¹, b¹, in a flange b², formed upon the standard, and which engage in tapped holes in the plates A, A¹, A². The top of the standard is bent over forming a hooked end B¹, to receive the angle of an elbow lever C, which is pivoted therein on the pivot pin c. The horizontal 75 arm of the elbow lever C is bent, inwardly if the set-screw d holding the needle D in the needle-bar D¹ is upon the inside, and outwardly if this set-screw d is upon the outside of the needle-bar so as to engage therewith and is provided with a curved slot c¹ in its outer extremity, in which the set-screw d works. A draw-lever E engages with the arm C² of the elbow lever C, the end of the lever E being bent around so as to form a hooked end e in which is pivoted the arm C² upon a pivot pin c². 80

The draw-lever E may be of any desired form. I 85 show it in the drawings as a flat bar, extending from the elbow-lever C to a point near the front of the attachment, where it is provided with a downwardly extending arm e¹ which passes through a slot a¹ formed in the top plate A², and engages in an eye f formed in one end 90 of the reciprocating plunger F, in the interior of the attachment. A hood G is attached to the top plate A² by screws g¹, g¹, at one side of the slot a¹, and projects over the top of the said slot a², sufficient space being left however between the hood G and the top surface of the 95 plate A² upon the other side of the slot to permit of the introduction of the draw lever E into the slot a¹, and its withdrawal therefrom as desired. The hood G covering the slot a¹, on top prevents the draw lever from jumping out of the slot, or being accidentally displaced therefrom. 100

In the interior of the attachment, and at the back side of the same, I pivot to the base-plate A upon a pivot pin h a peculiarly shaped four-armed plate H, which I hereinafter call the "alternator," the front arm h¹ of which 105 projects forwardly into the path of the plunger F, and

deflects the said plunger first to the one side and then to the other side of the attachment, as the plunger F is reciprocated forward and backward by the arm e^1 of the draw-lever E, which in turn is actuated by the set-screw d on the needle-bar D¹, working in the slot c^1 of the elbow lever C. The plunger F in its forward movements strikes the side arms h^2 , h^3 , of the alternator H alternately, causing the alternator to be turned from side to side of the attachment upon its pivot pin h . I form an aperture H¹ in the body of the alternator, and place therein a bow-spring h^5 , one arm of which has a bearing against the left side wall of the said aperture, and the other arm of which has a bearing against a pin h^6 , secured in the base-plate A, inside the aperture H¹, so that this spring acts constantly to turn the alternator toward the right hand side of the attachment. The pin h^6 also acts as a stop for the alternator preventing the same turning too far toward the right hand side. Upon the right hand side of the attachment is a catch arm I, pivoted on a pivot pin i to the base-plate A. This catch arm I is acted upon by a bow-spring i^1 , placed between the said catch arm and the side wall of the middle plate A¹, in such manner that it is constantly pressed toward the alternator. The catch arm I, is provided with a recess i^2 , which is adapted to receive and retain the arm h^3 of the alternator H, whenever the alternator is turned toward the left hand side of the attachment by the action of the plunger F upon the arm h^2 . In order that the alternator may be released from the catch-arm I when it is to be turned to the right hand side of the attachment, I provide the said catch arm with a nose i^3 which projects outwardly into the path of the plunger F. When the said plunger therefore is deflected toward the right hand side of the attachment by the arm h^1 , it goes forward and first strikes the nose i^3 , and turns the catch arm I upon its pivot-pin i , releasing the arm h^3 of the alternator from the recess i^2 , then the plunger goes forward further and strikes the arm h^3 , turning the alternator H upon its pivot-pin h , toward the right hand side of the attachment, in which position it is held by the action of the bow-spring h^5 , until the next forward movement of the plunger. I form a cavity J in the back end of the plate A¹ behind the alternator, so that the arm h^4 of the alternator, may swing freely therein, and I also form lugs or stops j , j , on the plate A¹ one on either side of the alternator H, against which the two sides of the arm h^4 of the said alternator may strike as the alternator is moved from side to side on its pivot pin h thus preventing too great a movement of the alternator in either direction.

50 A slot K is formed in the side of the attachment at a point opposite to the needle D (when the attachment is secured in position upon the sewing machine), and in this slot I place the bifurcated end of my pusher L, which I construct by forming two thin L shaped steel plates and bending the forward L shaped end of each of them upwardly at approximately a right angle to the rest of the plate forming upward flanges. I then place the plates one upon another leaving the two flanges separated a short distance apart and fasten them together by screws or rivets, or in any other desired manner, the bent portion or flange of the top plate forming the jaw l , and the bent portion or flange of the bottom plate forming the jaw l^1 of the pusher. The pusher L, so constructed I pivotally secure to the base-plate A on the pivot-pin l^2 , the middle-plate A¹ being cut away at this point

so that the pusher is free to oscillate upon the pivot-pin l^2 . In the body of the pusher I construct an aperture l^3 , and I secure a pin l^4 in the base-plate A, which projects upwardly inside of the aperture l^3 , on the left hand side thereof, and a bow-spring l^5 is inserted in the said aperture, one side of the said bow-spring having a bearing against the right hand side wall of the aperture l^3 , while the other side of the said bow-spring has a bearing against the pin l^4 , so that the said spring l^5 constantly acts upon the pusher L to retract it in the slot K in the side of the attachment. The pin l^4 also acts as a stop, the left hand side wall of the aperture l^3 abutting against it as the pusher is retracted by the spring l^5 and prevents too great an inward motion of the pusher. The left hand, or outer side of the pusher L is cut away somewhat, so that this side of the pusher will not project too far beyond the side of the attachment when the pusher is in its extended position.

The forward end of the plunger F (the end opposite to the draw-lever E) is free, and is rounded so that it will move easily and smoothly, along the sides of the alternator H as it is extended to do its work. When the pusher L is retracted in the slot K, the arm h^1 of the alternator H is turned toward the right hand side of the attachment, and at the next down-stroke of the needle-bar D¹, the draw-lever E will bring the plunger F forward, its free end striking the left side of the arm h^1 which deflects it toward the left hand side of the attachment. As this is done the left side of the plunger F bearing against the right side of the pusher L, presses the pusher outwardly, and as the plunger F continues its forward stroke, extends the bifurcated end, or jaws l , l^1 , out of the slot K, pushing the cloth away from the needle as hereinafter more fully explained. In order that the plunger F shall always be in position to do its work properly, I place a rectifying spring M, upon one side of the plunger, while on the other side the plunger has a bearing against the side of the pusher, and as the said plunger at all times works between these two parts any displacement is prevented, and the plunger is always held in a proper position to do its work. The ends of the spring M are seated in nicks m , m^1 , formed in the plate A¹.

In order to time the pusher, so that it will be extended at the proper moment to do its work, but will be and remain in its retracted position while the feed of the machine is at work, I form a cam surface N upon the left side of the plunger F (the side that bears against the pusher L) giving it the proper shape to extend the pusher, as the plunger F passes up the left side of the arm h^1 , at the precise moment it is required to act, and, as when the pusher is extended it should remain in its extended position until the needle passes down to make a stitch with the shuttle thread and again passes up out of the way of the cloth being stitched, I form a portion of the left side of the alternator in substantially the arc of a circle, the pivot-pin h being the center. The pusher L being fully extended when the end of the plunger F starts upon this arc, it will be firmly held in its extended position while the plunger is traversing the arc, and until it passes off therefrom. The moment the plunger F is withdrawn from the alternator H in its backward movement, the pusher L is instantly retracted by the action of the bow-spring l^5 , and remains in its retracted position until the plunger F is again caused to travel up the left

hand side of the alternator H, when it is again extended. The plunger L makes its forward movement at each down-stroke of the needle-bar D¹, acting alternately first upon one side and then the other side of the alternator H, being thus deflected or alternated by the arm h¹ of the alternator, which projects into the path of the plunger causing the latter to be deflected as above described, as the alternator is turned from side to side upon its pivot pin. When the alternator H is turned 10 toward the left side of the attachment so that the pusher is extended it is held in this position until the next forward stroke of the plunger F, by the catch-arm I, this catch-arm being required in order to hold the pusher and alternator in position against the back pressure of 15 the cloth being stitched. When the alternator is turned toward the right hand side of the attachment it is held in this position until the next forward stroke of the plunger F by the action of the bow-spring h⁵.

Slots O, O¹, are formed in the body of the attachment, which is adjustably held in position upon the base-plate of the sewing machine by a set-screw O². As the throat-plate of the machine is usually somewhat higher than the base-plate, I provide an adjusting screw O³ at the opposite side of the attachment, which passes 20 entirely through the plates A, A¹, A², engaging in a tapped hole formed therein, and has a bearing against the base-plate of the machine. By turning the adjusting screw O³ the one way or the other the attachment may be leveled and kept in a position to do its work 25 properly. When the attachment is placed upon the machine it should be adjusted so that when the pusher L is extended one jaw l will pass upon one side, and the other jaw l¹ upon the other side of the needle D when the latter is making its down-stroke, and so that the 30 jaws l, l¹, will push the cloth being stitched just clear of the needle.

In order to guide the cloth to be stitched to the needle I provide a suitable guide which is constructed as follows. A small plate P, extending along the front of the 40 attachment, is secured to the top plate A² by two screws p, p¹, which pass through two slots p², p³, formed in the plate P and engage in tapped holes (not shown) formed in the plate A², the plate P being free to move along the top plate A² in either direction, being held against displacement by the heads of the screws p, p¹. The plate P is provided with two lugs P¹, P². To the lug P¹ is attached by a screw or rivet p⁴ a guide plate P³ which passes down by the front side of the attachment and is bent around at a right angle and extends along the left 45 side of the attachment to a point near the slot K. The guide plate P³ may be moved upwardly or downwardly upon the screw or rivet p⁴. A bracket-piece R secured to the side of the attachment has an outwardly projecting end which is bifurcated forming jaws r¹, r². The lug P² of the plate P has a screw-threaded central aperture p⁵, in which engages the screw end s² of an adjusting screw S, having a milled-head s by which it may be turned, and being provided with a circumferential groove or channel s¹ in its head, which receives and 50 contains the jaws r¹, r², which pass upon either side of the said set screw. As the adjusting screw S is turned by its milled head s it is held by the jaws r¹, r², and its screw-threaded end s² working in the lug P² moves the plate P and consequently the guide-plate P³, toward 55 or away from the needle D as the set-screw S is turned

the one way or the other and consequently the guide-plate may be adjusted as necessary or desired.

In securing the attachment in place upon the machine the set-screw d upon the needle-bar D¹ is introduced into the slot o¹ of the elbow lever C; the attachment is then adjusted with respect to the needle D, as hereinbefore described, and secured in the adjusted position by tightening the set-screw O². It is then ready for work. At every alternate stitch the pusher L is extended out of the slot K, the jaws l, l¹ pushing the cloth 70 away from the needle, whereby a zig-zag line of stitches is produced.

In felling or blind-stitching (see Fig. 1) a hem 1 is first folded, then the part 2 is folded back over the hem 1, and is fed to the needle with the fold 3 uppermost, 80 and the single layer 4 underneath. If the pusher L is retracted at the first stitch, the guide plate P³ being properly adjusted, the needle D will pass down through the center of the cloth in the fold 3, and through the single layer 4, and form the first stitch. At the next 85 stitch the pusher L is extended, pushing the cloth clear of the needle, so that the second stitch is made on the outside of the cloth, this cycle of operations being repeated throughout the stitching. This method of stitching not only results in a true blind-stitching being 90 produced, but the raw edge of the single layer 4 is also overcast preventing raveling.

In serging the cloth is fed flat, a zig-zag line of stitches being formed along the edge of the cloth, overcasting it and preventing raveling.

In stoating the two pieces of cloth are laid one upon another and are fed flat, a line of zig-zag stitches being produced along the edge. When stitched and opened out, the two pieces of cloth will be securely stitched together, the seam being perfectly flat.

By suitably regulating the tensions and length of stitches a great variety of fancy and ornamental work, cordings, plaitings, pipings, etc., etc., may be produced.

It should be observed that while I employ a spring as an independent means for retracting the pusher in order to properly time its action, that in case of the breakage of the bow-spring l⁵ the pusher will be positively actuated by the plunger F the rear end of which will, as it is brought back by the draw-lever E, retract the pusher.

The function of the curve N on the alternator is to cause a dwell in the movement of the pusher. That is when the pusher moves out the end of the plunger moving on the curved edge of the alternator will simply slide along the same without having any further advancing 115 effect thereon and the pusher will be held out in one position while the plunger is passing over this curved part. It will be noticed that the parts are arranged so that the plunger as it retracts will with its heel turn the oscillating pusher so as to retract its forked end. In 120 case the spring fails the plunger will thus act positively to retract the pusher.

Having now described my invention what I claim as new and desire to secure by Letters Patent is:—

1. In an attachment for sewing machines, an oscillating pusher, means for operating the pusher from the needle bar to advance said pusher, and means operating independent of the needle bar and its connections for retracting the pusher when the pusher has completed its work and each time the feed of the cloth is to take place.

2. In an attachment for sewing machines, an oscillating 125

- pusher, means for operating the same from the needle-bar of the machine, said means having a back and forth movement throughout, and independent means for retracting the said pusher when its work is completed said pusher being retracted each time the feed of the cloth takes place.
5. In a sewing machine attachment, an oscillating pusher, a sliding plunger engaging with and acting upon the pusher to extend it at every alternate stitch, and independent means for retracting the said pusher as soon as it has completed its work, substantially as shown and described.
10. 3. In a sewing machine attachment, an oscillating pusher, a sliding plunger engaging with and acting upon the pusher to extend it at every alternate stitch, and independent means for retracting the said pusher as soon as it has completed its work, substantially as shown and described.
15. 4. In a sewing machine attachment, an oscillating pusher, means for operating the pusher from the needle-bar of the machine so that it will be extended at every alternate stitch, and independent means for retracting the pusher so that it will remain extended only when and while it is doing its work, said pusher being retracted when the feed of the cloth takes place, substantially as described.
20. 5. In a sewing machine attachment, a pusher, a sliding plunger having a cam surface engaging with and extending the pusher at every alternate stitch, means for operating the plunger from and in synchronism with the needle-bar of the machine, and independent means for retracting the pusher.
25. 6. In an attachment for sewing machines, a pusher having back and forth movements and means for moving the same out and in synchronously with a reciprocation of the needle bar, said pusher being retracted immediately its work is done and while the feed of the cloth is taking place, said means including connections to the needle bar, substantially as described.
30. 7. In a sewing machine attachment, a pusher, a sliding oscillatory plunger provided with a cam surface engaging with and actuating the pusher, an alternator controlling the movements of the plunger, and means for actuating the plunger from the needle-bar of the machine.
35. 8. In combination, a pusher, a plunger acting thereupon directly and means for operating the plunger synchronously from the needle bar and means for rendering one stroke of the plunger ineffective upon the pusher, substantially as described.
40. 9. In a sewing machine attachment an oscillating pusher, a plunger having a cam surface engaging with and actuating the pusher, means for actuating the plunger at every down stroke of the needle-bar, and for causing the plunger to extend the pusher on alternate strokes of the plunger.
45. 10. A sewing machine attachment having an oscillating pusher, a plunger engaging with and actuating the pusher, an alternator controlling the movements of the plunger, stops limiting the movements of the alternator, and means for actuating the plunger from the needle-bar of the machine.
50. 11. A sewing machine attachment, having an oscillating pusher, a plunger engaging with and directly actuating the pusher, an oscillating alternator controlling the movements of the plunger, a catch arm engaging with and holding the alternator during the extension of the pusher, and means for operating the plunger from the needle-bar of the machine.
55. 12. In a sewing machine attachment, a pusher formed in two parts, superimposed and one extending beyond the other each of said parts having a vertical portion which forms one of the jaws of the pusher.
60. 13. In a sewing machine attachment, a pusher formed in two parts, superimposed and one extending beyond the other each of the said parts having a vertical portion which forms one of the jaws of the pusher, the said two parts being suitably secured together, so that the said vertical portions shall be separated a sufficient distance so that they will pass, one on either side of the needle when the pusher is extended.
65. 14. In combination an oscillating pusher, a plunger engaging with and operating the pusher, a spring engaging with the plunger to hold the same to its work, an alternator controlling the movements of the plunger, and means for operating the plunger from the needle-bar of the machine.
70. 15. In combination an oscillating pusher, a spring, a plunger working between the pusher and the spring, an oscillating alternator controlling the movements of the plunger and causing the plunger to extend the pusher at every alternate down-stroke of the needle-bar, and means for operating the plunger from the needle-bar.
75. 16. In a sewing machine attachment, a pusher, a plunger, an oscillating alternator pivotally secured to the base-plate of the attachment, and stops limiting the movement of the alternator in either direction said parts controlling the movement of each other and one of said parts acting upon the pusher.
80. 17. In a sewing machine attachment, a pusher, a plunger, an oscillating alternator pivotally secured to the base-plate, stops limiting the movement of the alternator in either direction, a spring holding the alternator in one of its two positions, and a catch arm for holding the alternator in the other of its said positions said parts controlling the movement of each other and one of said parts acting upon the pusher.
85. 18. In combination an oscillating pusher, a plunger engaging with and operating the pusher, an alternator controlling the movements of the plunger, the said alternator having a portion of one of its sides formed in the arc of a circle, and means for operating the plunger from the needle-bar of the machine.
90. 19. In combination, a pusher, a plunger, and an oscillating alternator in the path of the plunger and arranged independent of the pusher, said plunger operating the pusher, said alternator being operated by the plunger substantially as described.
95. 20. In combination a pivoted oscillating pusher, a plunger, a pivoted oscillating alternator, the said alternator having an arm which projects into the path of the plunger and deflects the plunger so that it engages alternately with the two sides of the alternator and extends the pusher at every alternate down-stroke of the needle-bar.
100. 21. In combination a pivoted oscillating pusher, a plunger, a pivoted oscillating alternator, the said alternator having an arm which projects into the path of the plunger and deflects the plunger so that it engages alternately with the two sides of the alternator and extends the pusher at every alternate down stroke of the needle-bar and independent means for retracting the pusher.
105. 22. In a sewing machine attachment a pusher, a plunger, means for actuating the plunger an oscillating alternator pivoted to the base-plate of the attachment and adapted to control the movements of the plunger, stops limiting the movement of the alternator in either direction, a spring constantly acting upon the alternator in one direction, and a catch-arm pivoted at the side of the alternator and locking the alternator in place while the pusher is extended.
110. 23. In combination, the pusher and connections between the same and the needle bar including the lever C and the draw rod E and a hood G extending over the top of the draw rod and serving to retain the same in place, substantially as described.
115. 24. In combination, a pusher, a reciprocating oscillatory plunger acting directly against the same and an alternator for controlling the oscillatory movements of the plunger and locking means for the alternator, substantially as described.
120. 25. In combination, a pusher, a reciprocating oscillatory plunger acting directly against the same and an alternator for controlling the oscillatory movements of the plunger, and locking means for the alternator, said locking means being controlled by contact with the plunger, substantially as described.
125. 26. In combination, the needle bar, a pusher having a back and forth movement, a plunger for operating the pusher, means for operating the plunger from the needle bar and an alternator for controlling the movements of the plunger, said alternator having a curved bearing for the plunger whereby a dwell will occur in the advancing effect of the plunger on the pusher, substantially as described.
130. 27. In combination with a pusher, a plunger and an

alternator, one of said parts being arranged to operate the pusher and the said alternator having a curved surface over which the plunger may continue to slide without altering the position of the pusher, substantially as described.

28. In combination, a pusher, a needle bar, a plunger connected with the needle bar for operating the pusher directly, said plunger advancing the pusher as the needle bar descends and being retracted as the needle bar rises,

and means for retracting the pusher as the plunger retracts, substantially as described.

In witness whereof I have hereunto set my hand in presence of two witnesses.

GEORGE JOHN STEVENS.
